CLAIM

The ornamental design for the color harmony scale chart for music, as shown and described.

DESCRIPTION

The patent or application file contains at least one drawing executed in color. Copies of this patent or patent application publication with color drawing(s) will be provided by the Office upon request and payment of the necessary fee.

1. Color harmony scale chart for music

1.0 : Front View

This color harmony scale chart for music visualizes the harmonic relation between the 12 tones of western music tradition and the 7 modes generated by the major scale and the 5 modes generated by the minor scale in jazz music.
